UNITED STATES PATENT OFFICE.

BENJAMIN B. CONRAD AND FRANK SANDER, OF BROOKLYN, AND FREDERIC WARREN WRIGHT, OF BRONXVILLE, NEW YORK, ASSIGNEES TO AMERICAN NUMBERING MACHINE COMPANY, OF BROOKLYN, NEW YORK, A CORPORATION OF NEW YORK.

REMOVABLE TYPE FOR NUMBERING-WHEELS.

No. 923,773.

Specification of Letters Patent. Patented June 1, 1909.

Application filed March 1, 1909. Serial No. 480,771.

To all whom it may concern:

Be it known that we, BENJAMIN B. CONRAD and FRANK SANDER, citizens of the United States, residing at Brooklyn, New York, and FREDERIC WARREN WRIGHT, a citizen of the United States, residing at Bronxville, New York, have invented certain new and useful Improvements in Removable Type for Numbering-Wheels, of which the following is a clear, full, and exact description.

The object of this invention is to provide an improved means for holding in place removable type in a numbering machine wheel for example, such wheels as are used by the United States Government in printing the bank notes and legal tender certificates issued by the Government, particularly for permitting the change of the alphabetical character which generally precedes the serial number on such examples of paper money.

The main improvements in said wheel which are set forth in the following specification and shown in the drawings, consist of simplicity of construction and efficiency in securing a character in place as well as permitting of its ready removal at the proper time, and under the proper conditions.

The scope of the invention will be pointed out in the claims.

In the accompanying drawings, Figure 1 is a side elevation of a number wheel built in accordance with this invention. Fig. 2 is a view similar to Fig. 1 with part broken away through the vertical central plane of the wheel. Fig. 3 is a view similar to Fig. 2 showing the type and its retaining means removed. Fig. 4 is a plan view of Fig. 3. Fig. 5 is a detailed view similar to the sectioned part in Fig. 2, showing the type in the act of being inserted. Fig. 6 is a perspective view of the type. Fig. 7 is a perspective view of the catch holder. Fig. 8 is a section on line 8-8 Fig. 2.

As shown in the drawings, the wheel 1 is provided with a central opening 2 for the usual shaft of a numbering machine, and with openings 3 to receive the pins of the usual ratchet wheel not shown. The wheel in the example shown is provided with nine number sections represented by the figures within the circles as shown in Fig. 3. The type itself 4 is provided with a shank 5 hav-

ing a notch 6 with beveled sides, and preferably a beveled end 7. The wheel between characters one and nine is recessed for the reception of the rectangular block 8 of the type 4. The center of the recess is provided with a hole,—a round hole preferably,—9, to receive and fit the shank 5 of the type. Adjacent to the hole 9 we drill through the wheel the hole 10 and provide a communicating opening 11 between the hole 10 and the hole 9. We provide a circular plug 12 with 65 a slabbed side 13 with a circular hole 14 drilled therein, at right angles to the slabbed side, which hole 14 is provided with seats or shoulders 15 adjacent to the slabbed side. A spring 16 is inserted into the hole 14, and a latch 16 is provided and inserted in the hole 14 at the end of the spring. The latch 16 has a cylindrical part of greater diameter than the hole 11 in the wheel, and it has a projecting pin 17 preferably with a beveled end, 70 which projects into the opening 9, when the latch is in the position of Fig. 5, so that the type can be pushed past the beveled pin 17 and the pin spring back in the position as shown in Fig. 2, to engage and resiliently 80 hold the type in engagement with the notch 6 of the shank of the type. We preferably make the circular plug 12 which holds the resiliently held latch taper so that it can be fitted into the hole 10 from one direction, and 85 be tightly wedged in place.

We claim as our invention:

1. The herein described numbering machine wheel and removable type therefor, consisting of a type having a shank with a notch in the shank, said wheel being provided with two holes, one for the shank of the type and a second hole at right angles to the hole for the shank, and opening into the hole for the shank, and a resiliently held latch protruding into said hole for the shank of the type for engagement with the notched shank, said latch and its spring carried in a plug, said plug being located in a hole in the wheel at right angles to the plane of the wheel. 100

2. The herein described numbering machine wheel and removable type therefor, consisting of a type having a shank with a notch in the shank, said wheel being provided with two holes, one for the shank of the type and a second hole at right angles to the hole for the shank, and opening into the hole for the shank, and a resiliently held latch pro-

truding into said hole for the shank of the type for engagement with the notched shank, said latch and its spring carried in a plug, said plug being located in a hole in the wheel 5 at right angles to the plane of the wheel, said hole in the wheel being circular, and said plug being circular to fit, and having a hole drilled diametrically through the same for the reception of the spring and latch.

10 3. The herein described numbering machine wheel and removable type therefor, consisting of a type having a shank with a notch in the shank, said wheel being provided with two holes, one for the shank of the type 15 and a second hole at right angles to the hole for the shank, and opening into the hole for the shank, and a resiliently held latch protruding into said hole for the shank of the

type for engagement with the notched shank, said latch and its spring carried in a plug, 20 said plug being located in a hole in the wheel at right angles to the plane of the wheel, said hole in the wheel being circular, and said plug being circular to fit, and having a hole drilled diametrically through the same for 25 the reception of the spring and latch, a seat or shoulder for the spring at one end of the diametric hole of the plug.

Signed at Brooklyn N. Y. this 19th day of February 1909.

BENJAMIN B. CONRAD.
